US00D482142S

(12) **United States Design Patent** (10) Patent No.: **US D482,142 S**
Honda et al. (45) Date of Patent: ** Nov. 11, 2003

(54) **LAMP BULB**

JP	749276	12/1988
JP	999680	12/1997
JP	999680	2/1998
JP	10-334852	12/1998

(75) Inventors: **Hisashi Honda; Masazumi Ishida; Sadao Sakaguchi**, all of Yokosuka (JP)

* cited by examiner

(73) Assignee: **Toshiba Lighting & Technology Corporation**, Tokyo (JP)

Primary Examiner—Marcus A. Jackson
(74) Attorney, Agent, or Firm—Oblon, Spivak, McClelland, Maier & Neustadt, P.C.

(**) Term: **14 Years**

(57) **CLAIM**

The ornamental design for a lamp bulb, as shown and described.

DESCRIPTION

Dec. 11, 2000 (JP) 2000-035328

(51) LOC (7) Cl. **26-04**

(52) U.S. Cl. **D26/2**

(58) Field of Search D26/1, 2, 3; 313/313, 313/315, 317, 318, 491, 493, 567, 569; 315/56, 57, 58, 73

FOREIGN PATENT DOCUMENTS

JP 749276 11/1988

FIG. 1 is a front elevational view of a lamp bulb showing our new design, the rear elevational view being a mirror image of the front view shown;

FIG. 2 is a right side elevational view thereof, the left side elevational view being a mirror image of the side view shown;

FIG. 3 is an enlarged sectional view taken along line A—A in FIG. 1; and,

FIG. 4 is front elevational view thereof shown when in use with an outer bulb.

The outer bulb and electrical connectors shown in FIG. 4 are shown for illustrative purposes and form no part of the claimed design.
